LOCK FOR DOORS

Joseph J. Waitekaites, Waukegan, Ill.

Application August 21, 1945, Serial No. 611,799

1 Claim. (Cl. 70—150)

1

My invention relates to improvements in locks for doors, and the like, the primary object in view being to provide an all-purpose, safety lock of the cylinder lock type which is simple in construction, involves few parts, will not readily get out of order, is tamper-proof, and comparatively inexpensive to manufacture.

Other and subordinate objects, also comprehended by my invention, together with the precise nature of my improvements and the manifold advantages thereof, will be readily understood when the succeeding description and claim are read with reference to the drawings accompanying and forming part of this specification.

In said drawings:

Figure 1 is a view in vertical section illustrating my improved lock, in a preferred embodiment thereof, embodied in a door, the rear check plate of the lock being removed and the lock being partly broken away and shown in section,

Figure 2 is a view in vertical transverse section taken on the line 2—2 of Figure 1,

Figure 3 is a similar view taken on the line 3—3 of Figure 1 through the lock and showing the key for the lock,

Figure 4 is a view in horizontal section taken on the line 4—4 of Figure 1,

Figure 5 is a view partly in side elevation and partly in section illustrating the manner in which the frame bar is secured to the mortise plate,

Figure 6 is a view in front end elevation of the lock,

Figure 7 is a fragmentary view in rear elevation,

Figure 8 is a view in horizontal section taken on the line 8—8 of Figure 1,

Figure 9 is a view in vertical transverse section taken on the line 9—9 of Figure 7 and drawn to an enlarged scale,

Figure 10 is a fragmentary view in horizontal section taken on the line 10—10 of Figure 2,

Figure 11 is a view in perspective of the bolt-locking cylinder.

Referring to the drawings by numerals, my improved lock, in the illustrated, preferred embodiment thereof comprises a casing 1 adapted to be mortised, in the usual manner, into the front edge of a door 2 and comprising a U-shaped frame bar 3, a pair of front and rear check plates 4, 5 secured by screws 6 to the opposite sides of said bar 3, and a front mortise plate 7, of the usual type, for the front edge of the door 2 and from which plate the frame bar 3 extends horizontally with the cheek plates 4, 5 secured thereto

5 and with the free front ends of said frame bar 3 secured in said plate 7 by tongues 8 extending into and suitably fixed in slots 9 in said plate 7. As will be understood, the frame bar 3 forms the top, bottom and rear end of the casting 1. The mortise plate 7 is provided with the usual screw holes 10 for screws, not shown, for securing said plate 7 and the casting 1 in the door 2.

10 A bolt-locking cylinder 11 is rotatably fitted in a segmental recess 12 in the rear end of the frame bar 3 with its sides fitting between the cheek plates 4, 5 and with a pair of hubs 13, 14 on opposite sides thereof rotatably mounted in said cheek plates 4, 5. The bolt-locking cylinder 11 is provided on one side of its median plane with a peripheral recess 15 therein, the bottom of which forms a flat straight shoulder 16 at a right angle to said plane and the purpose of which will presently appear. The bolt-locking cylinder is 15 locked in either of two positions, in one of which the recess 15 is disposed forwardly, as regards the front and rear ends of the casing 1, and in the other of which said recess 15 is disposed rearwardly. In either of such positions of the bolt-locking cylinder 11 the shoulder 16 is disposed 20 vertically. For locking the bolt-locking cylinder 11, the usual diametrically opposite, coplanar series of two-part tumbler pins 17 are provided, there being two series of such pins radially slidable in said cylinder 11 with separate, enlarged outer end sections 18 projecting into corresponding series of bores 19 in the frame bar 3, as best shown in Figures 1 and 3, said pins 17 being spring-biased, as at 20, to seat said sections 18 25 in said cylinder 11 and to project the inner ends of said pins 17 into a keyway 21 in said cylinder 11. Cover plates 22 close the outer ends of the bores 19. The keyway 21 is of the usual flat, tortuous type to receive a similarly shaped key 23 30 having toothed edges 24 for moving said pins 17 outwardly when the key 23 is slid into said keyway 21. As will be understood, when the key 23 is thus entered in the keyway 21, the tumbler pins 17 are forced outwardly of said cylinder 11 to move the outer end sections 18 out of said cylinder 11 into the bores 19, in opposition to the spring 20, and said bolt-locking cylinder is thus unlocked and may be rotated by said key 23 into either of the two described positions. A spring-biased, transverse click pin 25 in the bolt-locking cylinder 11 yieldingly seating in seats 26, 27 35 in the front cheek plate 4 establishes the two positions of said cylinder 11. The keyway 21 is aligned transversely with a slot 28 in the door 2 and with a keyhole rotary disc 29 in an outside

escutcheon plate 30 on the front side of said door 2 secured to said door by screws 31.

A latch bolt 32 is slidably fitted in said casing 1 with the usual front beveled end 33 slideable in a rectangular aperture 34 in the mortise plate 7. The latch bolt 32 is endwise and front slideable to project the front end 33 thereof out of the mortise plate 7 into the usual keeper plate 35 on the door frame 36 to thereby latch the door 2, and to retract said end 33 out of said plate 35 to unlock said door 2. A pair of upper and lower edge stop lugs 37 on said latch bolt 32 project into longitudinal top and bottom edge recesses 38 in the frame member 3 and limit projection of the latch bolt 32 by engagement with the front ends of said recesses. A pair of coil springs 39 interposed, in said recesses 38, between the rear ends of the recesses and said lugs 37, yieldingly project the latch bolt 32 into latching position. The rear end of the latch bolt 32, when the bolt-locking cylinder 44 is rotated into the second-described locked position thereof to dispose the shoulder 46 rearwardly, is engaged by said cylinder 44 and locked against retraction, as shown in Figures 1 and 4. In the second-described locked position of said bolt-locking cylinder 44, with the shoulder 46 disposed forwardly, said latch bolt 32 is unlocked and may be retracted into the recess 45 against said shoulder 46. A side recess 39' in the rear end of the latch bolt 32 accommodates the portion of the bolt-locking cylinder 44 opposite the recess 45 when the latch bolt 32 is retracted to permit retraction of said latch bolt.

For retracting the latch bolt 32 a pair of inside and outside finger lever 40, 40' are pivoted intermediate the ends thereof as at 41, 41' in a pair of pocket 42, 42' formed in an inside escutcheon plate 33', and the outside escutcheon plate 30 said levers 40, 40' extending out of said plates 30, 33' to be rocked vertically. The beforementioned screws 31 secure the inside escutcheon plate 30' to the door 2. The finger levers 40, 40' extend through slots 43, 43' in said escutcheon plates 33', 30 and into the casing 1 by way of slots 44, 44' in the rear and front cheek plates 5, 4 and with the inner ends thereof overlying arms 45, 45' of a pair bell cranks pivoted, as at 46, 46' on the inner sides of the cheek plates 5, 4, in side recesses 47, 47' in the latch bolt 32, the other arms 48, 48' of said bell cranks being adapted to bear against shoulders as at 49 formed by the rear side walls of the recesses 47, 47'. By pulling up on the outer ends of said finger levers 40, 40' the inner ends of said levers are caused to rock the arms 48, 48' of the bell cranks against the shoulder 49 and thereby retract the latch bolt 32. During retraction of the latch bolt 32 the inner ends of the finger levers 40, 40' slide on the arms 45, 45' of said bell cranks. Thumb grip pieces 50, 50' are suitably attached to the inside and outside escutcheon plates 33', 30 over the finger grip levers 40, 40' to facilitate operation of said levers. The door 2 is slotted, as at 51, 51' to permit play of the finger grip levers 40, 40' therein. Preferably, the thumb grip pieces 50, 50' are fitted in the pockets 42, 42' as shown in Figure 10, with the pivots 41, 41' extending therethrough and are attached to said plate 33', 30 by a screw 52, 52' to secure the thumb pieces in place.

A safety catch, or night latch, is provided for the latch bolt 32 and which comprises a cylinder-like member 53, with a flat side 54, rotatably mounted in the upper leg of the frame bar 3 to extend crosswise of the top edge of the latch bolt 32, the arrangement being such that said member

53 may be rotated into a transverse upper edge notch 55 in the latch bolt 32 to lock said bolt against retraction, or rotated to oppose its flat side 54 to the upper edge of the latch bolt 32 and thereby unlock said latch bolt. With its flat side 54 rotated in opposed relation to the upper edge of the latch bolt 32, said member 53 is prevented from rotating when the latch bolt 32 is retracted. A spring-pressed click pin 56 in said member 53 10 coaxing with seats 57 in the front cheek plate 4 yieldingly establishes the described different positions of said member 53. Reduced ends 58, 59 on said member 53 are journaled in the cheek plates 4, 5, respectively. For operating the member 53, a lever 60 is fixed, by a pin 61, on the reduced end 62 of a spindle 63 fitted in a recess 64 in the door 2 and aligned with said member 53, with the reduced end 62 journaled in and projecting out of the escutcheon plate 33'. The spindle 63 is keyed at its other end, as at 65, to the end 59 of said member 53.

As will now be seen, my improved latch may be locked by key from the outside of the door 2 only, the described safety catch, or night latch, 25 providing for locking on the inside of the door 2. Also, the latch bolt 32 may be retracted to unlatch the door 2 from both the inside and outside of said door and by means of the finger grip levers 40, 40'.

30 The foregoing will, it is believed, suffice to impart a clear understanding of my invention since the operation of the lock has been set forth in connection with the description of the structure thereof, and, therefore, further description is 35 not deemed to be required.

Manifestly, the invention, as described, is susceptible of modification without departing from the inventive concept, and right is herein reserved to such modifications as fall within the 40 scope of the appended claim.

What I claim is:

A lock for a door comprising a casing adapted to be mortised into the door, a latch bolt slidably mounted in said casing for projection and retraction into and from latching position, respectively, and having a rear end, a latch bolt-locking cylinder in said casing rotatable into bolt-locking and unlocking positions, respectively, and engaging said rear end of said bolt in the locking 45 position thereof, spring-biased means to lock said cylinder in both positions thereof, and means to unlock said locking means and rotate said cylinder including a key, said cylinder having a side recess for accommodating said rear end of the 50 latch bolt in the unlocking position of the cylinder and said rear end of the latch bolt having a side recess therein for accommodating a portion of the cylinder in the unlocking position of said cylinder.

60 JOSEPH J. WAITEKAITES.
